(57) **CLAIM**

The ornamental design for a combination communication and sensor hub, as shown and described.

DESCRIPTION

FIG. 1 is a front perspective view of a combination communication and sensor hub, showing our new design;

FIG. 2 is a front view thereof;

FIG. 3 is a back view thereof;

FIG. 4 is a side view thereof;

FIG. 5 is a top view thereof; and,

FIG. 6 is a bottom view thereof.

The broken lines immediately adjacent the shaded areas represent the bounds of the claimed design while all other broken lines are directed to environment and are for illustrative purposes only; the broken lines form no part of the claimed design.
